(57) **CLAIM**

The ornamental design for a lacrosse helmet visor, as substantially shown and described.

DESCRIPTION

FIG. 1 is a perspective view of a lacrosse helmet visor showing my new design.

FIG. 2 is a top plan view of the lacrosse helmet visor of FIG. 1.

FIG. 3 is a bottom plan view of the lacrosse helmet visor of FIG. 1.

FIG. 4 is a front elevational view of the lacrosse helmet visor of FIG. 1.

FIG. 5 is a rear elevational view of the lacrosse helmet visor of FIG. 1.

FIG. 6 is a right side elevational view of the lacrosse helmet visor of FIG. 1.

FIG. 7 is a left side elevational view of the lacrosse helmet visor of FIG. 1; and,

FIG. 8 is another perspective view of the lacrosse helmet visor of FIG. 1 attached to a lacrosse helmet shown in broken lines. The broken lines shown in the drawings represent portions of the lacrosse helmet visor that form no part of the claimed design.
